UNITED STATES PATENT OFFICE.

WILLIAM A. LUNDQUIST, OF SAN FRANCISCO, CALIFORNIA.

WINDOW CLEANER.

Application filed February 7, 1923. Serial No. 617,621.

To all whom it may concern:

Be it known that I, WILLIAM ALFRED LUNDQUIST, a citizen of the United States, residing in the city and county of San Francisco and State of California, have invented a new and useful Improvement in a Window Cleaner, of which the following is a specification.

My invention relates to improvements in window cleaner for street car windows and the like wherein squalgees are carried by endless chains to simultaneously clean both sides of a pane.

The primary object of my invention is to provide an improved device to facilitate the cleaning and clearing to vision through car windows and the like.

Another object is to provide an improved device wherein both sides of the window may be cleaned simultaneously.

A further object is to provide a device which may be installed upon car windows of the character in common use without interfering with the ordinary movement of such window.

Another object is to provide a device of simple and durable construction which may be readily installed upon existing windows without marring the outward appearance thereof.

I accomplish these, and other objects by means of the device disclosed in the drawings forming a part of the present specification, wherein like characters of reference are used to designate similar parts throughout said specification and drawings and in which,

Fig. 1 is a front elevation of a street car showing the application of my invention thereto.

Fig. 2 is a broken enlarged vertical section of the window taken upon the line 2—2 of Fig. 1 in the direction indicated.

Fig. 3 is a broken front elevation of a portion of the window frame, parts being broken away and shown in section to show the manner in which the sprockets are mounted.

Fig. 4 is a horizontal section taken upon the line 4—4 of Fig. 3 in the direction indicated.

Fig. 5 is a transverse section of the squalgee showing the construction thereof.

Referring particularly to the drawings the numeral is used to designate in general a street car having a window 2 in the front

thereof through which the driver observes his course. The accumulation of moisture upon the window is, as is well known, a source of great danger both to the occupants of the car and to persons crossing its course. To facilitate the removal of such accumulated moisture so that the window may be kept clean and clear without material inconvenience to the driver of the car I provide squilgees 3 and 4 upon the inner and outer sides of the window respectively. The squilgees are normally arranged to occupy positions at opposite ends of the window and are carried by common actuating members so that a movement of one from top to bottom will cause a corresponding movement of the other squilgee from bottom to top in a manner hereinafter more fully described.

In the preferred construction disclosed in the drawings the frame 6 of the window is recessed as at 7 at top and bottom adjacent the sides of the pane and notches 8 are formed upon the frame along the edge of the pane upon the inner and outer surfaces of the pane. A transverse bore 9 communicates with each recess 7 to admit a sprocket 11 provided with bearing portions 12 and 13, one of which engages a counter bore 14 formed in the back of the recess 7 and the other a recess 16 formed in the end of a plug 17 arranged to be inserted into the bore 9 to retain the sprocket in position and to normally enclose the same within the recess 7.

Endless chains 18 are mounted over the sprockets at each side of the window to extend along opposite sides of the pane adjacent the edges thereof. Rods 19 are secured between the chains 18 in any suitable manner to extend across the pane, one of said rods being arranged to normally occupy a position at the top of the pane, and the other to occupy a corresponding position at the bottom of the pane upon the other side thereof. Arcuate rubber bands 20 are secured upon the rods to form the squilgees above referred to, said bands being preferably formed from material slightly more

than half round and having a corresponding concave groove of a diameter slightly less than the diameter of the rods 19 so that when the band is slightly spread the rod 19 will be admitted into the groove and the contraction of the rubber will tend to hold the band in place. Cement or other securing means may, of course, be applied be-

tween the band and the rod to prevent any displacement of the band relative to the rod.

The outer convex surface of the bands are arranged to engage the surfaces of the window pane so that when the squilgee is moved in either direction accumulated moisture will be wiped simultaneously from both sides of the pane and the glass thus cleaned 10 and the vision cleared.

Strips 21 are secured in the notches 8 formed upon the frame, said strips being arranged to lie flush with the outer surface of the frame and extending past the chains 15 18 to normally enclose the same and to engage the outer sides of the squilgees. The notching of the edges of the frame to receive the strips 21 is important for the reason provision must be made to avoid increasing 20 the thickness of the frame which is ordinarily arranged to be moved into a recess in the front of the car. By setting the strips into the notches 8 no increase in thickness is caused and the window may thus be operated in the usual manner without any interference by the application of my invention thereto. The strips 21 perform a further duty in maintaining the squilgees in 25 operative contact with the window pane. The strips 21 are arranged to engage the back of the squilgees at each end thereof, so that when moved thereunder the rubber bands 20 will be held against the pane. In operation, the inner squilgee is normally positioned at either extreme position. When 30 it is desired to remove moisture from the window, the inner squilgee is grasped by the driver of the car and moved to its extreme position, such movement causing the actuating chains to be moved over their respective sprockets and the outer squilgee thereby moved from its normal position at the opposite edge of the window to its other extreme position, the two squilgees being thus moved 35 simultaneously to remove accumulated moisture from both sides of the pane. The squilgees may then be immediately returned to the original position, or remain in the moved position until moisture has again accumulated upon the window at which time a movement in the opposite direction to the starting position will result in a clearing of the vision. It is ordinarily preferable to 40 keep the inner squilgee at the bottom of the pane and the outer squilgee at the top so that when moved to clear the pane the heavy collection of moisture upon the outer side will be moved downwardly, the lighter accumulation of moisture due to the condensation 45 of moisture from the air upon the inner side of the pane being readily removed by the upward movement of the squilgee.

While I have shown what I now consider to be the preferred construction of the device, it is of course, subject to modification in

numerous ways without departing from the spirit of my invention. In similar manner, the device may be applied to the drivers' windows of locomotives, ferry boats, and other conveyances wherein windows mounted in wooden frames are provided. I, therefore, do not desire to restrict myself closely to the precise details of construction and application, but wish to avail myself of such modifications as may fall within the scope 75 of the appended claims.

Having thus described my invention, what I claim as new and desire to secure by Letters Patent is:

1. In a window cleaner, the combination 80 with a window frame, recesses formed at the top and bottom adjacent the sides thereof and transverse bores communicating between the recesses and the edges of the frame, of sprockets mounted within the recesses, said sprockets each being provided with bearing portions extending outwardly from both sides thereof one of which portions is rotatably engaged within a bore 85 formed at the back of the recess; plugs adapted for insertion into the transverse bores to engage the other bearing portion of the adjacent sprocket, and to enclose the sprockets within the frame; endless chains mounted over the sprockets at each side of the frame; and squilgees mounted between the chains upon the inner and outer sides of the frame for movement across a pane 90 mounted within the frame.

2. In a window cleaner, the combination 100 with a window frame having recesses formed at the top and bottom adjacent the sides thereof and transverse bores communicating between the recesses and the edges of the frame, of sprockets mounted within the recesses, said sprockets each being provided with bearing portions one of which portions is rotatably engaged within a bore formed at the back of the recess; plugs adapted for insertion into the transverse to engage the 105 outer bearing portion of the adjacent sprocket and to enclose the sprockets within the frame; endless chains mounted over the sprockets adjacent the sides of a pane secured within the frame; squilgee connected 110 between the chains upon opposite sides of the pane; and strips mounted within notches formed in the sides of the frame, said strips being set flush with the surface of the frame to permit manipulation of the frame in 115 opening and closing, and extending over the chains to enclose said chains and to engage the ends of the squilgees whereby said squilgees are held in engagement with the pane 120 for cleaning the same when moved thereacross.

In witness whereof I hereunto set my signature.

WILLIAM A. LUNDQUIST.
